 of New Jersey

Application July 26, 1950, Serial No. 175,916

6 Claims. (Cl. 200—138)

1

This invention relates to a structurally and functionally improved detecting apparatus, especially useful in operating alarm or registering apparatus when excessive heat conditions dangerous to property arise; the present invention thus lending itself ideally to the initiation of an alarm under such circumstances. However, apparatus constructed in accordance with the present teachings may also be employed for purposes other than merely registering or sounding an alarm.

It is an object of the invention to furnish a unit of this type which may be conveniently mounted or installed in desired locations of diverse character and which will operate efficiently where a pre-determined fixed temperature is exceeded or where a rise of temperature has occurred in less than a certain minimum period of time.

Moreover, in accordance with the present teachings the apparatus will be self-restoring and will not be affected by dust or other foreign materials.

An additional object is that of furnishing a device of this type which will include relatively few parts, each individually simple and rugged in construction and operating over long periods of time with freedom from all difficulties.

With these and other objects in mind reference is had to the attached sheet of drawings illustrating one practical embodiment of the invention and in which:

Fig. 1 is a sectional side view of the detector taken along the line 1—1 and in the direction of the arrows as indicated in Fig. 2;

Fig. 2 is a bottom plan view of the device with certain of the encasing portions removed and with others broken away to disclose inner structures;

Fig. 3 is a transverse sectional view taken along the line 3—3 and in the direction of the arrows as indicated in Fig. 2; and

Fig. 4 is a sectional top plan view taken along the line 4—4 and in the direction of the arrows as indicated in Fig. 1 and with certain of the parts also broken away to show underlying structures.

In these views the numeral 5 indicates a base formed of di-electric material such as a suitable plastic. This base may be provided with openings 6 through which fastening bolts or other mounting units extend. The base also preferably includes a central portion 7 formed with an opening 8 and additionally embraces various surfaces contoured to provide mountings for the

2

parts as hereinafter described. The base may terminate in a downwardly extending flange 9 provided with one or more lead-accommodating openings 10. The latter may be initially closed by "knockouts" and which are removed when necessary for the convenient passage of leads connected to the unit.

A cover preferably in the form of a dome 11 is provided. This unit is formed of a metal having high thermal conductivity. Preferably there extends across the dome an integral rib portion 12. Such rib portion serves to strengthen the dome and make it resistant to flexing or distortion. Disposed within the groove thus formed in the inner face of the dome is a bimetallic strip 13. The latter may be secured by rivets or soldering at a point adjacent that at which the dome is supported on the base. The upper end of strip 13 is free and preferably carries an insulating disk 14. A shoulder may define the outermost or central portion 7 of the base. This shoulder has a diameter equal to that of the dome 12. As shown, these parts are overlapped and a press fit exists between them. Prior to mounting the cooperating surfaces may be coated with a film of cement. In this manner the parts are retained against displacement and an air tight fit is assured.

Disposed within dome 12 and upon the outermost portion of the base is a strip 15. The latter is conveniently formed of bronze. One of its ends is preferably secured against displacement with respect to the base by, for example, a terminal in the form of a bolt 16. Its central portion is bowed upwardly in line with the insulating disk 14. Its opposite end is extended downwardly and outwardly. That end may terminate in a laterally extending portion 17 spaced from the outer face of the base. Carried by the base and underlying this end of strip 15 is a contact which may embrace a set screw 18. From the latter a strip 19 extends in electrical engagement with a terminal 20. Similarly a conducting strip 21 may extend from bolt 16 through to terminal 22. Leads (not shown) are connected to terminals 20 and 22. These leads, in accordance with conventional construction, are coupled to a source of electric current supply and to the registering or other mechanism which is to be actuated when conditions of danger exist.

Disposed inwardly of the central portion 7 of the base is a diaphragm 23. The latter is preferably formed of corrosion-resistant metal and conveniently provided with concentric corrugations. While it will be highly sensitive to pres-

sures of low value, it will also be relatively strong and resistant to shocks and other abuses. As shown, it may centrally mount a contact 24 of suitable metal. Its side edges are conveniently flared outwardly to provide a flange portion 25. The latter bears against the inner face of the central portion 7 of the base and is maintained in this position by a mounting ring 26 of dielectric material. To assure an air tight fit a film of cement may be applied to the flange 25 prior to the mounting of the diaphragm. Therefore, when ring 26 is brought into firm contact with flange 25 and the latter is in turn caused to intimately engage the inner face of base portion 7, a seal is provided which will remain effective for long periods of time even when subjected to high temperatures.

Underlying diaphragm 23 and bearing against the lower edge of ring 26 is a bridge portion 27. The latter may conveniently be formed of bronze. It adjustably mounts a contact screw 28. As shown, especially in Figs. 1 and 2, strip 19 is continued beyond the assembly indicated at 18 and is secured in electrical connection with screw 28. That screw extends in line with contact 24. A cover 29 is applied to the inner surface of the base and closes the lower portion of the assembly. This cover will have a relatively snug fit with respect to adjacent surfaces. However it is provided with openings or notches through which strips 19 and 21 extend. By virtue of these and/or other openings passages are provided such that an adequate air flow may occur into and from the space directly enclosed by the cover.

A breather valve or passage is furnished by conveniently utilizing a tube 30. The latter has its upper end extending in communication with the space defined by dome 12. The body of this tube may extend below the central portion 7 of the base to a point adjacent the inner face of cover 29. Tube 30 is constricted as at 31 to furnish a substantially reduced passage. Thus, in effect, a metering structure is provided which will allow of a seepage of air into and from the base enclosed by the dome. Obviously, other forms of breather tube or valve structures might be employed in lieu of that herein illustrated. As is apparent and under all circumstances the parts are so proportioned or calibrated that a flow corresponding to that suitable for the needs of a given installation is provided for. The central portion 7 of the base is formed with a further passage which is continued in the bore of a plug 31' extending into the space defined by cover 29. This bore permits of a setting of the parts, as hereinafter described. After the setting has once been effected then the plug bore may be sealed by a block or stopper 32.

The parts are assembled to provide a unit as shown in the drawings. So assembled ring 26 will maintain diaphragm 23 in mounted position and sealed as aforescribed. As the securing bolts or screws mounting bridge member 27 are tightened that member will bear against the lower edge of ring 26 to maintain it against any probability of displacement. Thus, danger of air leakage is prevented. Contact screw 28 is adjusted to be spaced a proper distance from contact 24. This result is achieved by connecting plug 31' with a source of air under predetermined pressure and to create a similar pressure within dome 12. Screw 28 is, under these circumstances, brought into engagement with contact 24. That screw is now locked conven-

iently by a nut and locking ring assembly. With the source of air under pressure disconnected from plug 31 the bore of the latter may be sealed by the block or stopper 32. In an abundance of caution a cement film may be applied to the locking assembly for screw 28 as well as to the block or stopper 32 and the parts of the set screw assembly 18. Other parts may likewise be coated if desired. As afore brought out the breather tube or valve 30 provides a passage of reduced cross section having an area proper for the needs of a given installation. This installation—contrary to systems as heretofore provided—uses no medium for the air flow. Accordingly changes in the rate of air flow caused by atmospheric conditions or conditions existing in plants is, in effect, eliminated. Spring strip 15 is so applied to the base and maintained against movement with respect to the same that it cannot change its horizontal position adjacent bolt 16. Insulating disk 14 or its equivalent prevents electrical connection being established between this strip and the dome 12 or other undesired parts. The laterally extending end portion 17 of strip 15 may be conveniently silver plated or otherwise treated to assure of a ready flow of current. The same is true of contacts 24 and screws 18 and 28. Due to the fact that strip 13 is in direct engagement with the dome 12, heat will be immediately transferred from the latter to the bimetallic strip when heat is generated exteriorly of the unit. Any excess of wire connected to terminals 20 and 22 may be housed within the space existent between cover 29 and the outer edge of flange 9.

Under normal conditions of temperature variation the air confined within dome 12 is maintained at atmospheric pressure. This will be because of the valve 30 which permits air to slowly enter or escape from this space according to then existing conditions. However, any sudden change of temperature as caused by an abnormal heat condition in an area or compartment protected by one or more of the detectors will expand the air within dome 12. This will create a pressure on the inner face of diaphragm 23 because the pressure will be transmitted through opening 8. As a result contact 24 will engage set screw 28. Thus, the circuit is closed and an alarm is given and/or desired apparatus is actuated. As will be apparent, the creation of an adequate pressure to achieve this result will occur because the opening afforded by valve or tube 30 is so small that the air expanded by the heat cannot escape fast enough to prevent an engagement between contact 24 and set screw 28. As will also be apparent this rate of rise system or structure can be adapted to normal as well as abnormal temperature conditions simply by increasing or decreasing the breathing capability of valve 30 and by adjustments of the set screw 28.

Used according to a fixed temperature system or unit it will be understood that if the rate of rise is not rapid as in the prior consideration of the device, heat in any area protected by the detector is readily transferred through the metal of dome 12 to the bimetallic strip 13. The latter is confined in its movements towards and away from the central portion of strip 15. As strip 13 is subjected to increased temperature it will bear against the central portion of spring 15 and force the end of the same into contact with the assembly 18. Thus an alarm will be given as soon as the temperature has reached a certain

pre-determined point. By using bimetals with different characteristics and by properly adjusting the parts, the fixed temperature characteristic of the unit can be depended upon to operate under ordinary as well as under extraordinary high and intermediate heat conditions as they arise in any given installation.

After the condition causing the high temperature has been corrected and the temperature drops below the operating point of the detector, 10 the bimetallic strip 13 will return to its original position. Accordingly the apparatus will be reset for a subsequent operation. The same is true in considering the rapid rate of rise structure or system characteristics of the unit. As will 15 be apparent due to the provision of the breather valve 30, the diaphragm and other self-restoring parts will return to a normal position after the dangerous condition has ceased to exist.

As will be understood due to the fact that the breather tube 30 uses no medium for the air flow, the dangers of clogging of that tube with consequent faulty operation of the device are avoided. Under certain conditions plug 31' may be eliminated and merely the opening through which the breather tube 30 passes used for testing purposes. The configuration of strip 15 may be varied in numerous respects. Also if desired and contrary to the showing in the drawings the position of the dome 17 might be shifted through 180°. Under these circumstances, the bimetallic strip 13 would extend above and adjacent the bolt 16. With such an arrangement of parts the movements of the spring strip 13 will be achieved in a more desirable manner.

Thus a spot detector or unit is provided which will furnish a structure to dependably respond to a rapid rate of rise, as well as the exceeding of a pre-determined fixed temperature. It is apparent that among others the several objects of the invention as specifically aforesaid are achieved. Obviously numerous changes in construction and rearrangement of the parts might be resorted to without departing from the spirit of the invention as defined by the claims.

I claim:

1. A detector including in combination a base of insulating material, a shell of heat conducting material secured to said base, a bimetallic strip having one end secured against movement with respect to said shell and its body extending adjacent the inner face of the latter and terminating in a free end at a point intermediate the edges of said shell, a spring strip disposed within said shell, means for securing one end of said spring strip against movement with respect to said base, a contact carried by said base and engageable by the opposite spring strip end and said bimetallic strip engaging the body of said spring strip with its free end at a point between the ends of said spring strip to rock the latter around the end secured to said base and cause said opposite strip end to have amplified movement towards and out of engagement with said contact.

2. A detector including in combination a base of insulating material, a shell of heat conducting material secured to said base, a bimetallic strip having one end secured against movement with respect to said shell and its body extending adjacent the inner face of the latter and terminating in a free end at a point intermediate the edges of said shell, a spring strip disposed within said shell, means for securing one end

of said spring strip against movement with respect to said base, a contact carried by said base and engageable by the opposite spring strip end, said bimetallic strip engaging the body of said spring strip with its free end at a point between the ends of said spring strip to rock the latter around the end secured to said base and cause said opposite strip end to have amplified movement towards and out of engagement with said contact, said shell being formed with a groove in its inner face, said groove reinforcing said shell and said bimetallic strip in one of its extreme positions, having substantially its entire body disposed within said groove in contact with the adjacent shell face.

3. A detector including in combination a base of insulating material, a shell of heat conducting material secured to said base, a diaphragm also secured to said base and providing in cooperation with said shell an air pressure chamber, a contact supported by said base and adapted to be placed in electrical connection with said diaphragm as the latter flexes in response to increase in air pressure within said chamber, means providing a breather structure to permit of a controlled flow of air into and from said chamber, a bimetallic strip having one end secured against movement with respect to said shell and its body extending adjacent the inner face of the latter and terminating in a free end at a point intermediate the edges of said shell, a spring strip disposed between said shell and diaphragm with its ends extending into the space intervening said shell and diaphragm, means for securing one end of said spring strip against movement with respect to said base, a contact carried by said base and engageable by the opposite strip end, the free end of said bimetallic strip engaging the body of said spring strip at a point between the ends of the latter to rock said spring strip around its secured end and cause said opposite strip end to have amplified movement toward and out of engagement with said contact and a centrally apertured portion forming a part of said base and intervening said spring strip and diaphragm.

4. A detector including in combination a base of insulating material, a shell of heat conducting material secured to said base, a diaphragm also secured to said base and providing in cooperation with said shell an air pressure chamber, a contact supported by said base and adapted to be placed in electrical connection with said diaphragm as the latter flexes in response to increase in air pressure within said chamber, means providing a breather structure to permit of a controlled flow of air into and from said chamber, a bimetallic strip having one end secured against movement with respect to said shell and its body extending adjacent the inner face of the latter and terminating in a free end at a point intermediate the edges of said shell, a spring strip disposed between said shell and diaphragm with its ends extending into the space intervening said shell and diaphragm, means for securing one end of said spring strip against movement with respect to said base, a contact carried by said base and engageable by the opposite strip end, the free end of said bimetallic strip engaging the body of said spring strip at a point between the ends of the latter to rock said spring strip around its secured end and cause said opposite strip end to have amplified movement towards and out of engagement with said contact, a cen-

trally apertured portion forming a part of said base and the latter being recessed in line with said portion, an outwardly extending flange at the edge of said diaphragm, said diaphragm being disposed within said recess and with its flange portion adjacent the surface of the central base portion and a mounting ring bearing against said flange and the adjacent base surfaces to maintain said diaphragm in substantially air-tight engagement with said base.

5. A detector including in combination a base of insulating material, a shell of heat conducting material secured to said base, a diaphragm also secured to said base and providing in cooperation with said shell an air pressure chamber, a 15 contact supported by said base and adapted to be placed in electrical connection with said diaphragm as the latter flexes in response to increase in air pressure within said chamber, means providing a breather structure to permit of a controlled flow of air into and from said chamber, a bimetallic strip having one end secured against movement with respect to said shell and its body extending adjacent the inner face of the latter and terminating in a free end at a point intermediate the edges of said shell, a spring strip disposed between said shell and diaphragm with its ends extending into the space intervening said shell and diaphragm, means for securing one end 20 of said spring strip against movement with respect to said base, a contact carried by said base and engageable by the opposite strip end, the free end of said bimetallic strip engaging the body of said spring strip at a point between the ends of the latter to rock said spring strip around its secured end and cause said opposite strip end to have amplified movement towards and out of engagement with said contact, a centrally apertured portion forming a part of said base and the latter being recessed in line with said portion, 25 an outwardly extending flange at the edge of said diaphragm, said diaphragm being disposed within said recess and with its flange portion adjacent the surface of the central base portion, a mounting ring bearing against said flange and the adjacent base surfaces to maintain said diaphragm in substantially air-tight engagement with said base and a bridge portion secured to said base and bearing against said ring to prevent a displacement of the latter.

6. A detector including in combination a base of insulating material, a shell of heat conducting material secured to said base, a diaphragm also secured to said base and providing in cooperation with said shell an air pressure chamber, a contact supported by said base and adapted to be placed in electrical connection with said diaphragm as the latter flexes in response to increase in air pressure within said chamber, means providing a breather structure to permit of a controlled flow of air into and from said chamber, a bimetallic strip having one end secured against movement with respect to said shell and its body extending adjacent the inner face of the latter and terminating in a free end at a point intermediate the edges of said shell, a spring strip disposed between said shell and diaphragm with its ends extending into the space intervening said shell and diaphragm, means for securing one end 20 of said spring strip against movement with respect to said base, a contact carried by said base and engageable by the opposite strip end, the free end of said bimetallic strip engaging the body of said spring strip at a point between the ends of the latter to rock said spring strip around its secured end and cause said opposite strip end to have amplified movement towards and out of engagement with said contact, a centrally apertured portion forming a part of said base and intervening said spring strip and diaphragm and a cover secured to said base and enclosing the outer surface of said diaphragm.
